UNITED STATES PATENT OFFICE.

JOSEPH D. CAEL AND GRAHAM L. OGLE, OF WILMINGTON, DELAWARE.

CAR-COUPING.

SPECIFICATION forming part of Letters Patent No. 396,919, dated January 29, 1889.

Application filed October 12, 1888. Serial No. 287,894. (No model.)

To all whom it may concern:

Be it known that we, JOSEPH D. CAEL and GRAHAM L. OGLE, both citizens of the United States, and residents of Wilmington, New Castle county, Delaware, have invented certain Improvements in Car-Couplings, of which the following is a specification.

The object of our invention is to construct a simple and easily-operated car-coupling of the interlocking-hook type, and this object we attain in the manner hereinafter set forth, reference being had to the accompanying drawings, in which—

Figure 1 is a sectional plan view showing the two coupling-heads coupled. Fig. 2 is a side view of the improved coupling. Fig. 3 is a diagram view showing the heads in the act of uncoupling. Fig. 4 is a diagram view showing them in the act of coupling, and Figs. 5 and 6 are views of modified forms of coupling-hook for the head.

A is the coupling-head, made either in the form of a casting in one piece or formed of wrought-metal plates secured together in any suitable manner. In the drawings we have shown the head composed of wrought-metal plates separated by filling-pieces b b', so as to form a recess or slot, a, between the plates, the recess extending into the filling-piece b, as shown at a'. In the upper and lower plates are slots c c', one near the inner end of the coupling-head and the other near the outer end of the same. In the recess a is a coupling-hook, D, Fig. 1, this coupling-hook having a head, d, which engages with the head of the hook carried by the opposite coupling-head. The hook D is tapered toward its point d' for the same purpose as in other couplings of this class.

From the body of the hook D project pins g g', the ends of which are contained in the slots c c' in the upper and lower plates of the coupling-head. Near the rear of the coupling-hook D, on the inner side, is a projection, e, between which and the hook-head d is formed a recess, f, for the reception of the hook of the opposite coupling-head. This projection e is wider than the shank of the hook, being in fact as wide as the depth of the coupling-head or of the head d of the hook, so that, as the opposite hook approaches, its end d' strikes the projection e, as shown in Fig. 4,

thus forcing the hook in the direction of its arrow and coupling the heads together, as more fully described hereinafter.

55

In the outer face of the hook D is a recess, forming a shoulder, i, and pivoted at j in the recess a, directly back of the portion b' of the coupling-head, is a dog, E, which is held against the outer face of the coupling-hook D and caused to engage with the shoulder i by a spring, F, attached to a pin, h, on the head. Connected to the dog E is a chain, k, which can be led to any convenient portion of the car, or may be attached to a lever, as circumstances suggest, so that the dog can be withdrawn without the necessity of the brakeman going between the cars. A pin, p, is placed at the back of the spring F for the purpose of stiffening the spring and preventing undue outward movement of the dog E.

65

The slot c' is curved transversely, so that the outer portion of the hook will swing transversely on the forward movement of the hook, and the slot c is inclined slightly in the opposite direction, whereby when the dog releases the hook and there is an outward pull upon the latter it will be moved in the direction of its arrow, Fig. 3, the outer portion of the hook swinging transversely, so that a combined forward and transverse movement is obtained, thus uncoupling the hooks of the two heads.

75

I prefer to form projections d' on the heads of each of the hooks D, the object of these projections being to prevent the accidental transverse separation of the heads, thus overcoming all risk of uncoupling, except that due to the forward movement of the hook.

80

When it is desired to couple the cars, the retaining-dog of one of the hooks is withdrawn, allowing the hook to assume the position shown in Fig. 4. When the opposite coupling-hook comes in contact with the projection e of the loose hook, as shown in Fig. 4, it forces the said loose hook backward, and consequently causes the front portion of the hook to be moved transversely toward the opposing hook, so as to engage therewith, and as the opposing hook still pushes upon the loose hook it will finally cause said loose hook to assume such position that the dog E can snap into position, as in Fig. 1, thus locking the hook securely in place and coupling the two heads.

95

100

- To release the coupling, the dog of one or other of the couplings is moved out of engagement with the hook D, so that on the separation of the coupling-heads, as shown 5 in Fig. 3, the head of the stationary hook will force the head of the loose hook transversely out of engagement with it and thus effect the uncoupling, the loose hook then being in position to be recoupled at any time.
- 10 When the parts are in the position shown in Figs. 3 and 4, the pressure of the dog E upon the coupling-hook will keep said hook in the transversely-extended position, unless the hook is pushed in intentionally.
- 15 The hooks shown in Figs. 1, 2, 3, and 4 are intended for coupling not only with like hooks, but with hooks of the Miller type, while the hook shown in Fig. 5 is the preferred form of hook when the cars are equipped solely with 20 our improved coupling-heads, Fig. 6 showing the form of coupling-hook used in connection with hooks of the Janney type; but it will be understood that the form of the hook may be altered without departing from our invention.
- 25 The hook D has a heel, *w*, which, when the heads are coupled, bears against the filling-piece *b'* of the head and serves to relieve the pins *g'* of the strain due to bumping or lateral 30 thrust upon the hooks.
- Instead of forming slots in the top and bottom of the coupling-head, pins may be secured to the heads and slots formed in the coupling-hooks, the result being the same.
- 35 Each coupling-hook is provided with a slot, *s*, for the reception of a link, and an orifice, *t*, for the insertion of the usual coupling-pin, so as to permit coupling with ordinary cars by link and pin.
- 40 We claim as our invention—
1. The combination, in a car-coupling, of the head, a coupling-hook, and a retainer therefor, with longitudinal and transverse guides for said hook, by which the hook will have a 45 combined longitudinal and transverse move-

ment on its release from the retainer, substantially as described.

2. The combination, in a car-coupling, of the recessed head having slots therein, as described, with a coupling-hook having pins 50 adapted to said slots, and a spring-dog engaging with the outer face of said coupling-hook, substantially as described.

3. The combination, in a car-coupling, of the coupling-head, the sliding hook having a 55 head, *d*, and an extension or projection, *e*, forming with the head a recess, *f*, for receiving the hook of the opposing head and a retainer for said hook, substantially as specified.

4. The combination, in a car-coupling, of the 60 head, with a hook, and longitudinal and transverse guides for said hook, with a projecting lug, *d'*, on the engaging-head of said hook, substantially as and for the purpose set forth.

5. The combination, in a car-coupling, of 65 the recessed head having longitudinal slots *c* at the rear and transverse curved slots *c'* at the outer end, with a coupling-hook having pins working in said slots, substantially as described.

6. The combination of the slotted coupling-head, the locking-dog, and the coupling-hook having pins adapted to the slots in the head, and having a heel bearing against an abutment in the head and serving to relieve the 70 pins from strain, all substantially as specified.

7. The combination of the coupling-head, its hook, the swinging locking-dog, the spring acting thereon, and a pin acting as a backing for the spring and as a stop for the outward 75 movement of the dog, all substantially as specified.

In testimony whereof we have signed our names to this specification in the presence of two subscribing witnesses.

JOSEPH D. CAEL.
GRAHAM L. OGLE.
